THOMAS B. MILLER AND ALLEN H. COX, OF SEATTLE, WASHINGTON, ASSIGNEES OF ONE-HALF TO SMITH CANNERY MACHINES COMPANY, OF SEATTLE, WASHINGTON, A CORPORATION.

INTERFERENCE-PREVENTER FOR USE IN WIRELESS-TELEGRAPH SYSTEMS.

1,123,910.

Specification of Letters Patent.

Patented Jan. 5, 1915.

Application filed November 16, 1912. Serial No. 731,803.

To all whom it may concern:

Be it known that we, THOMAS B. MILLER and ALLEN H. Cox, citizens of the United States, residing at Seattle, in the county of King and State of Washington, have invented a certain new and useful Improvement 5 in Interference-Preventers for Use in Wireless-Telegraph Systems, of which the following is a specification.

Our invention relates to improvements in devices known as interference preventers that may be connected with the circuits of a receiving apparatus of a wireless telegraph station whereby radiant Hertzian electrical 10 waves representing intelligible signals, which emanate from a desired particular one of several other different distant wireless telegraph stations that are generating and sending out such waves, exclusively 15 may be perceived and interpreted by a telegraph operator; and the object of our invention is to provide a wireless telegraph station with a system of circuits and apparatus associated therewith that shall be 20 adapted to be adjusted to receive and clearly make readable to an operator the weak electric waves from a most distant station, or from a station of smallest power which is sending signals represented by the weakest 25 of electric waves, without interference or interruption by, or a perception by the operator of, stronger electrical waves which at the same time may be emanating from a nearby or more powerful station. This object we attain by electrical circuits and devices connected therewith which are illustrated in the accompanying drawings, 30 wherein—

Figure 1 is a diagrammatic representation 40 of the essential mechanism of our invention as connected with the circuits of a receiving apparatus of a wireless telegraph station and Fig. 2 is a perspective view showing the most essential portions of such 45 mechanism and the relative positions of their operative parts.

Like reference numerals indicate like parts throughout the drawings.

Referring to Fig. 1 of the drawings, 3 50 is the primary winding of an air-core transformer 4, one end of which winding is connected with a ground 5 while its other end 6 may be connected with the antenna of a wireless station. The secondary winding 7

of the air-core transformer 4 forms a part 55 of an oscillating circuit, one of its terminals being connected with one terminal of a telephone 8 and with one terminal of a condenser 9 while its other terminal is connected through a rectifying detector 10 with 60 the other terminal of the condenser 9 and with the other terminal of the telephone 8.

Connected in parallel with the rectifying detector 10 is a circuit 11 which includes a circuit-breaking switch 12 and a pair of 65 movably adjustable needles, 13 and 14 preferably of small steel wire highly polished, disposed and supported at a right angle with each other. The needle 13 is fastened in and projects in a horizontal direction 70 from one end of an iron armature 15 which is mounted to oscillate on a shaft 16 that may turn in suitably supported bearings, not shown. Beneath the other end of the armature 15 is an electro-magnet 30 which 75 may be connected with a source of varying electric current, as with an electric battery 31 whose current is varied by a buzzer 32, as shown in Fig. 2, whose varying energy may serve, in a manner well known, to cause 80 the armature 15 to vibrate or oscillate to move the needle 13 up and down. Upon the top of the armature 15 is mounted flat resilient springs 17 and 18, as more clearly shown in Fig. 2, whose effective action may 85 be varied respectively by adjusting screws 19 and 20 which project through suitably supported lugs 21 and 22 respectively, whereby the amplitude of vibration of the armature 15 may be controlled. The needle 90 14 is attached to the upper end of a spiral spring 23 whose lower end is secured to the upper end of a lever 24, more clearly shown in Fig. 2, which lever 24 is secured to a flat flexible spring 25 that is supported by a 95 bracket 26 whereby the needle 14 normally may be disposed in a vertical position to rest against the horizontal needle 13. Integral with the bracket 26 is an upright projection 27 adapted to support an adjusting 100 screw 28 which may serve to adjust the position of the lever 24 to cause the needle 14 to have a desired pressure against the needle 13 as the needle 13 moves upwardly and downwardly in response to vibrations of the 105 armature 15. In operation the needles 13 and 14 are well covered with a film of oil, of suitable quality, whereby there shall

always be present a thin film of oil between the needles 13 and 14 at their points of contact with each other. Such film of oil may be maintained by disposing on each or one of the needles 13 and 14 a little ball 29 of fibrous material, as of cotton, well saturated with a desired quality of oil.

- The circuit 11, including the needles 13 and 14, being connected in parallel with the 10 rectifying detector 10, may serve to short circuit electrical waves of alternating polarity which are sufficiently powerful to break through the film of oil that is present between the needles 13 and 14 but can not 15 serve to short-circuit waves of alternating polarity which are not strong enough in electro-motive force to break through such film of oil and thus such weaker waves of alternating polarity are confined to a path 20 leading through rectifying detector 10 wherethrough only waves of like polarity may find passageway; and since waves of like polarity may not readily be transmitted through the condenser 9 they are forced to 25 pass through the telephone 8 to cause it to make perceptibly audible sounds; while the waves of alternating polarity that are sufficiently strong to break through the film of oil between the needles 13 and 14 find passageway of little resistance around the rectifying detector 10 and then may pass readily through the condenser 9 (which can offer little or no resistance to waves of alternating polarity) instead of passing through the 30 parallel path within which is connected the telephone 8, and thus such strong waves of a nearby station may not actuate the telephone 8 or other electrical translating device that might be likewise disposed in a 35 circuit parallel with the condenser 9. Thus, in operation, strong waves of an alternating polarity of a nearby station or of a distant but more powerful station, acting on the primary winding 3, may induce corresponding waves in the secondary winding 7 40 whereupon, with the circuit-breaking switch 12 closed, such corresponding waves may break through the film of oil between the needles 13 and 14 and find passageway 45 through the circuit 11 and condenser 9 without affecting the receiving telephone 8; but weakened waves of alternating polarity emanating from a far distant station, not being able to break through the film of oil 50 between the needles 13 and 14, are subjected to the action of the rectifying detector 10 whereby only waves of a like polarity can pass therethrough and such like waves are adapted to actuate the telephone 8 and are 55 not adapted to be short circuited through the condenser 9, and therefore only the very weak wave signals of a desired one of sev- 60

eral different stations may be heard in the telephone 8 when the air-core transformer 4 is properly tuned to such desired station in 65 a manner well known, although a number of nearer stations may be emanating powerful signal waves.

The purpose of vibrating the armature 15 is to cause the needle 13 to engage with the 70 needle 14 at different points successively whereby oil may be distributed always to form a film of oil between the two needles 13 and 14 since if the needle 13 be stationary then minute electrical sparks might cause a 75 carbonization of the oil film and fresh oil might not find its way between the points of engagement of the needles 13 and 14.

We have shown only one form of mechanism for controlling and adjusting the 80 needles 13 and 14 and for constantly changing the position of the point of engagement between such needles but various other forms of mechanisms may be employed for such purpose without departing from the 85 spirit of our invention.

What we claim is:

1. In the receiving system of a wireless telegraph station, the combination with an oscillating circuit, of a pivoted magnet armature that is adapted by suitable electro-magnetic means to be vibrated, a metal electrode secured to and projecting from said armature, a second metal electrode flexibly and adjustably mounted on suitable supporting means and adapted to be maintained in lubricated engagement with said first named metal electrode, and means for maintaining a lubricated contact between said electrodes. 95

2. In a receiving apparatus for a wireless telegraph station, the combination with an oscillating circuit that includes the secondary winding of a transformer, of a condenser, a rectifying detector, said condenser and said detector being connected in said oscillating circuit in series with said secondary winding, a translating device connected to said oscillating circuit in parallel with said condenser, and a shunt circuit connected to said oscillating circuit in parallel with said rectifying detector within which shunt circuit is included a resistance adapted to obstruct the passage of weak electric waves and to break down to permit the passage of strong electric waves. 100 105 110 115

In witness whereof, we hereunto subscribe our names this sixth day of November A. D., 1912.

THOMAS B. MILLER.
ALLEN H. COX.
